METHOD OF AND MEANS FOR PRODUCING ALTERNATING CURRENTS

Filed Jan. 29, 1920

Inventor:
Albert W. Hull,
by *Alfred S. Deni*
His Attorney.

UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

METHOD OF AND MEANS FOR PRODUCING ALTERNATING CURRENTS.

Application filed January 29, 1920. Serial No. 354,913.

My present invention relates to the production of alternating currents and more particularly continuous high frequency alternating currents such as are commonly employed for radio signaling.

The object of my invention is to provide a simple and convenient apparatus for producing high frequency currents from a direct current source or a pulsating current source of comparatively low frequency.

In carrying my invention into effect I employ an electron discharge device having an electron emitting cathode and an anode enclosed in an evacuated receptacle and preferably arranged in circular symmetry with respect to each other about an axis. The electrodes of this device are included in a circuit containing a source of current. The current flowing between the two electrodes may be controlled or varied in amplitude by means of a magnetic field in the receptacle in a direction parallel to the axis of the electrodes, or at right angles to the electrostatic field between the electrodes. If this magnetic field is varied between certain limits, depending in each case upon the structure of the device and the voltage applied to the electrodes, the current flowing between the electrodes may be varied between a maximum value which may be the value of the current which would flow in the absence of any magnetic field and a minimum value which may be substantially zero. In practice it will probably be found desirable in most cases to provide a constant magnetic field of such a value that the current flowing between the electrodes will be somewhat reduced from the amount which would flow in the absence of a magnetic field. The current flowing in the device may then be varied between maximum and minimum values by means of a supplementary variable magnetic field which is produced by means of the current flowing between the electrodes and which alternately assists and opposes the constant magnetic field.

The novel features which I believe to be characteristic of my invention are set forth with particularity in the appended claims.

The invention itself, however, both as to its organization and method of operation will best be understood by reference to the following description taken in connection with the accompanying drawing in which Fig. 1 illustrates diagrammatically one way in which my invention may be carried into effect, and Fig. 2 is a characteristic curve showing the relation between the current flowing between the electrodes at constant voltage and the strength of the magnetic field.

As indicated in Fig. 1 an electron discharge device is employed comprising an evacuated receptacle 1 which is preferably of tubular form and which contains a filamentary cathode 2 and an anode 3 of cylindrical form, the two electrodes being arranged in circular symmetry with respect to each other; that is, the active surfaces of the two electrodes are substantially surfaces of revolution about a common axis which is preferably the major axis of the receptacle 1. While this arrangement of electrodes is desirable for securing the best results it is not essential as satisfactory results may be obtained with arrangements of the electrodes which do not involve circular symmetry. A source of current 4 is connected to the two terminals of the cathode 2 for heating it to incandescence to cause it to emit electrons for carrying current across the evacuated space between the two electrodes. An external circuit between electrodes 2 and 3 includes a source of current 5, an impedance device 6, an inductance represented conventionally at 7 but which actually is wound around the receptacle 1, and a variable capacity 8 in shunt to the inductance. A constant magnetic field is provided by means of a coil 9 likewise surrounding the receptacle 1, and supplied with current from a direct current source 10, the strength of the magnetic field thus furnished being adjustable to a desired value by means of a variable resistance 11. It may also be desirable to include a choke coil 12 in the circuit which supplies current to the coil 9 in order to prevent alternating current from circulating in that circuit by reason of the inductive relation between coils 7 and 9.

The circuit between electrodes 2 and 3 may also include a coil 13 which is coupled to a coil 14, which is included in circuit with the antenna 15, thereby supplying the high frequency current which is generated to the antenna circuit.

When the cathode is maintained at a suitable temperature by the heating current and a suitable voltage is impressed upon the electrodes, current will flow in the plate or output circuit, 5, 7, 13, 6. With no modifying magnetic field the value of this current is determined by various factors, among which are the impressed voltage, cathode temperature, size and geometric relation of the electrodes and the resistance of the output circuit. The electrons which carry or constitute this current travel outwardly from the cathode to the surrounding anode in substantially radial paths. When the magnetic field is generated in a direction substantially parallel to the axis of the electrodes and substantially at a right angle to the paths of the electrons, the electrons are deflected and caused to travel in spiral paths about the cathode on their way to the anode. As the field strength is increased the spiral paths of the electrons become longer until finally at a critical magnetic field strength, characteristic of any particular device, some of the electrons fail to reach the anode by reason of this deflection, thereby causing a decrease in the current. When the field strength is still further increased above this critical value the electron current falls and is substantially reduced to zero.

The relation between the magnetic field and current flowing in the plate or output circuit is indicated by the diagram of Fig. 2, the values of the magnetic field being plotted as abscissæ and the corresponding current values as ordinates, the impressed voltage being constant. It will be observed that as the strength of the magnetic field is increased from zero, the current remains substantially constant until the magnetic field has reached a value represented by *oa*. Further increase of field strength produces a rapid reduction of current until at a field strength *ob*, the current has fallen to substantially zero.

The apparatus which I have described may be employed in various ways to produce oscillations and various explanations may be advanced as to the manner in which the apparatus operates to produce oscillations. While I do not wish to limit myself to any particular method of operation, the following description is given to indicate one manner in which the apparatus may be operated.

The constant magnetic field may be adjusted to a value substantially equal to or somewhat greater than that represented by *oa* in Fig. 2. The magnetizing coil 7 may

be so arranged and connected to the source 5 that the current flowing therethrough from this source will produce a magnetic field which adds to the constant magnetic field. Under these conditions when the circuits are completed current will start to flow in the plate circuit but this current instead of coming up to the maximum value will only rise to a value intermediate the maximum and minimum values. In building up to this value at which the combined magnetic fields produced by coils 7 and 9 will prevent further increase of current, the condenser 8 will be charged. When the current in the plate circuit reaches the maximum value to which it can build up under these conditions the condenser 8 discharges through coil 7 producing a current in the opposite direction to that produced by the source 5. The magnetic field produced by this current will oppose the constant magnetic field and allow the building up again of current through the coil 7 from the source 5. The building up of this current will again produce a magnetic field which adds to that of the coil 9 and causes the current to decrease. The frequency of these changes in current will depend upon the natural period of the oscillating circuit which comprises the condenser 8 and coils 7 and 13. Current flowing in the plate circuit may be considered as a direct current having an alternating component superimposed thereon, this alternating component being the component which is effective in varying the magnetic field in the device, and hence varying the current in the plate circuit. This action is assisted by the impedance 6.

The alternating current produced in this way, if of radio frequency, may be modulated or interrupted in any desired way for radio signaling purposes either telephonic or telegraphic. It is also apparent that the alternating current produced may be employed for wire signaling or for any other purpose for which it is desired to employ alternating currents.

While I have shown and described only one form of my invention, I do not wish to be limited to this particular form as it is apparent that many variations in the structure of the devices employed, as well as in the circuit connections used, may be made without departing from the scope of my invention as set forth in the appended claims.

What I claim as new and desire to secure by Letters Patent of the United States, is:—

1. The combination in a system for producing alternating currents of an electron discharge device comprising an evacuated receptacle containing a cathode adapted to emit electrons independently of gas ionization and an anode arranged in substantially circular symmetry and unobstructed spacial

- relation with respect to said cathode, means for producing a constant magnetic field in said receptacle in the space between said electrodes, an external circuit between said cathode and anode containing a source of current, and means for producing by current flowing in said circuit a magnetic field which is superimposed upon the constant magnetic field.
10. 2. The method of producing alternating currents which consists in producing a stream of electrons in substantially radial paths between an electron emitting cathode and a cooperating electrode, producing a constant magnetic field in a direction substantially at a right angle to the paths of the electrons and periodically substantially interrupting the electron stream between cathode and co-operating electrode by means of a magnetic field produced by current carried by said electron stream and superimposed upon said constant magnetic field.
15. 3. The method of producing alternating currents which consists in producing a stream of electrons in substantially radial paths between an electron emitting cathode and a cooperating electrode, and periodically substantially interrupting the electron stream between cathode and anode by means of a magnetic field which is in a direction substantially at a right angle to the paths of the electrons and which is produced by current carried by said electron stream.
20. 4. The combination in a system for producing alternating currents of an electron discharge device comprising an evacuated receptacle containing a cathode adapted to emit electrons independently of gas ionization and an anode arranged in substantially circular symmetry and unobstructed spacial relation with respect to said cathode, means for producing a constant magnetic field in said receptacle in the space between said electrodes, an external circuit between said cathode and anode containing a source of current, and an inductive winding surrounding said receptacle and connected in series relation in said external circuit.
25. 5. The combination in a system for producing alternating currents of an electron discharge device comprising an evacuated receptacle containing a cathode adapted to emit electrons independently of gas ionization and an anode arranged in unobstructed spacial relation with respect to said cathode, means for producing a constant magnetic field in said receptacle, an external circuit between said cathode and anode containing a source of current, an inductive winding surrounding said receptacle and connected in series relation in said external circuit, and a capacity in shunt to said inductive winding.
30. 6. The combination in a system for producing alternating currents of an electron discharge device comprising an evacuated receptacle containing a cathode adapted to emit electrons independently of gas ionization and an anode arranged in unobstructed spacial relation with respect to said cathode, means for producing a constant magnetic field in said receptacle, an external circuit between said cathode and anode containing a source of current, an inductive winding surrounding said receptacle and connected in series relation in said external circuit, and a capacity in shunt to said inductive winding.
35. 7. The combination in a system for producing alternating currents of an electron discharge device comprising an evacuated receptacle containing a cathode adapted to emit electrons independently of gas ionization and an anode arranged in unobstructed spacial relation with respect to said cathode, means for producing a constant magnetic field in said receptacle, an external circuit between said cathode and anode containing a source of current, an inductive winding surrounding said receptacle and connected in series relation in said external circuit, and a capacity in shunt to said inductive winding.
40. 8. The combination in a system for producing alternating currents of an electron discharge device comprising an evacuated receptacle containing a cathode adapted to emit electrons independently of gas ionization and an anode, means for producing a constant magnetic field in said receptacle in the space between said electrodes, an external circuit between said cathode and anode containing a source of current, an oscillatory circuit which is resonant to the frequency of the currents to be produced, and an inductive winding surrounding said receptacle, included in said oscillatory circuit, and connected in series relation in said external circuit.
45. 9. The combination in a system for producing alternating currents of an electron discharge device comprising an evacuated receptacle containing a cathode adapted to emit electrons independently of gas ionization and an anode arranged in substantially circular symmetry and unobstructed spacial relation with respect to said cathode, an external circuit between said cathode and anode containing a source of current, and an inductive winding surrounding said receptacle and supplied with current from said external circuit so as to produce a magnetic field in the space between said electrodes.
50. 10. Means for producing alternating currents comprising an electron discharge device having a cathode adapted to emit electrons independently of gas ionization and an anode arranged in substantially circular symmetry and unobstructed spacial relation

with respect to said cathode enclosed in an evacuated receptacle, an external circuit between said electrodes containing a source of current, an impedance in said circuit, means for producing a constant magnetic field in said receptacle in the space between said electrodes, and means for producing by energy supplied from said source of current a variable magnetic field which is superimposed upon the constant magnetic field.

11. The combination in a system for producing alternating currents of an electron discharge device comprising an evacuated receptacle containing a cathode adapted to emit electrons independently of gas ionization and an anode arranged in substantially circular symmetry and unobstructed spacial relation with respect to said cathode, an external circuit between said cathode and anode containing a source of current, means for producing a constant magnetic field in said receptacle and means for producing by energy supplied from said source of current, a variable magnetic field which is superimposed upon the constant magnetic field.

12. The combination in a system for producing alternating currents of an electron discharge device comprising an evacuated receptacle containing a cathode adapted to emit electrons independently of gas ionization and an anode arranged in substantially circular symmetry and unobstructed spacial relation with respect to said cathode, an external circuit between said cathode and anode containing a source of current, and means for producing by current flowing in said current a magnetic field in the space between said electrodes.

13. The combination in a system for producing alternating currents of an electron discharge device comprising an evacuated receptacle containing a cathode adapted to emit electrons independently of gas ionization and an anode arranged in substantially circular symmetry with respect to said cathode, an external circuit between said cathode and anode containing a source of current, an oscillatory circuit and an inductive winding surrounding said receptacle and included in said oscillatory circuit and connected in series relation in said external circuit.

14. The combination in a system for producing alternating currents of an electron discharge device comprising an evacuated receptacle containing a cathode adapted to emit electrons independently of gas ionization and an anode arranged in substantially circular symmetry and unobstructed spacial relation with respect to said cathode, means for producing a constant magnetic field in said receptacle in the space between said electrodes, an external circuit between said cathode and said anode containing a source of current, an oscillatory circuit supplied

with current from said external circuit, and means for producing a magnetic field by current in said oscillatory circuit which will be superimposed upon said constant magnetic field.

15. The method of operating an electron discharge device, having an electron emitting cathode and an anode enclosed in an evacuated receptacle, to produce oscillations which consists in producing a constant magnetic field in the space between the electrodes, producing between the electrodes a flow of current which is carried by negative electrons moving in substantially radial paths substantially independent of gas ionization and producing by means of current flowing between said electrodes a variable magnetic field which is superimposed upon the constant magnetic field in the space between the electrodes and which is of sufficient value to periodically substantially interrupt the flow of electrons.

16. The method of operating an electron discharge device, having an electron emitting cathode and an anode enclosed in an evacuated receptacle, to produce oscillations which consists in applying a potential to said electrodes to produce a flow of current between said electrodes which is carried by negative electrons substantially independent of gas ionization, and producing by means of current flowing between said electrodes a variable magnetic field in the space between said electrodes in a direction substantially at right angles to the electrostatic field between said electrodes and which is of sufficient value to periodically substantially interrupt the flow of electrons.

17. The method of operating an electron discharge device, having an electron emitting cathode and an anode enclosed in an evacuated receptacle, to produce oscillations which consists in applying a potential to said electrodes to produce a flow of current between said electrodes which is carried by negative electrons substantially independent of gas ionization, producing a constant magnetic field between said electrodes in a direction substantially at right angles to the electrostatic field between said electrodes and producing by means of current flowing between said electrodes a variable magnetic field which is superimposed upon said constant magnetic field and which is of sufficient value to periodically substantially interrupt the flow of electrons.

18. The method of operating an electron discharge device, having an electron emitting cathode and an anode enclosed in an evacuated receptacle, to produce oscillations which consists in applying a potential to said electrodes to produce a flow of current between said electrodes which is carried by negative electrons substantially independent of gas ionization, producing a constant

magnetic field between said electrodes in a direction substantially at right angles to the electrostatic field between said electrodes and producing by means of current flowing between said electrodes, a variable magnetic field which is superimposed upon said constant magnetic field and which alternately

assists and opposes said constant magnetic field and which is of sufficient value when it assists said constant magnetic field to substantially interrupt the flow of electrons. 10

In witness whereof, I have hereunto set my hand this 27th day of January 1920.

ALBERT W. HULL.
